United States Patent Office

Des. 212,054
Patented Aug. 20, 1968

212,054

MOVIE CAMERA

Dale R. Caldwell, 400 Deming Place,
Chicago, Ill. 60614

Filed Aug. 29, 1967, Ser. No. 8,412

Term of patent 14 years

(Cl. D61—1)

FIG. 1 is a side elevational view of the movie camera showing my new design;

FIG. 2 is a top plan view of the movie camera;

FIG. 3 is a front elevational view of the movie camera; and

FIG. 4 is a rear elevational view of my movie camera. The dominant features of my new design are shown in solid lines in the drawing.

I claim:

The ornamental design for a movie camera, substantially as shown and described.
